UNITED STATES PATENT OFFICE.

MAX ROSNER, OF NEW YORK, N. Y., ASSIGNOR, BY DIRECT AND MESNE ASSIGNMENTS,
TO EDWIN D. HENDERSON, JR., OF NEW YORK, N. Y.

FIRE-ESCAPE.

1,149,689.

Specification of Letters Patent. Patented Aug. 10, 1915.

Application filed December 21, 1912. Serial No. 738,005.

To all whom it may concern:

Be it known that I, MAX ROSNER, a citizen of the United States, and a resident of New York, county and State of New York, have invented a certain new and useful Improvement in Fire-Escapes, of which the following is a full, clear, and exact specification.

This invention relates to a class of devices adapted to be used for saving persons when in a burning structure.

My invention has for its object primarily to provide a fire escape, or device designed to be employed upon a building, or other structure to permit persons confined therein when endangered by fire to readily escape without injury, and wherein is employed a chute adapted to be composed of one or more integrally constructed sections so as to provide a continuous passage therethrough and which sections are disposed on inclines in opposite relative directions from each story of the building, in order to avoid too precipitous a descent for persons to slide down the chute especially when applied to high structures.

Another object of the invention is to provide in the chute a number of freely rotatable members arranged adjacent to each other transversely of the chute and which serve to force the persons entering the chute to move in a downwardly direction therethrough.

A further object of the invention is to provide a fire escape which is susceptible of being constructed entirely of cement, or other material which is non-inflammable and a non-conductor of heat, or may be made of cement and metal combined in a manner to prevent the flames of a burning structure from contacting with and heating the metal, and a still further object of the invention is to provide a form of chute upon the top of which may be constructed a stairway.

With these and other objects in view, the invention will be hereinafter more particularly described with reference to the accompanying drawings, which form a part of this specification, and will then be pointed out in the claims at the end of the description.

In the drawings, Figure 1 is a fragmentary view of a building with one form of fire escape embodying my invention ap-

plied thereto, parts of which are broken away. Fig. 2 is a view, partly in section, taken on the line II—II of Fig. 1. Fig. 3 is a view, partly in section taken on the line III—III of Fig. 1. Fig. 4 is a fragmentary view, partly in section, taken on the line IV—IV of Fig. 2. Fig. 5 is a top plan, partly fragmentary and partly in detail, of a number of the rollers and rails used in conjunction with the fire escape. Fig. 6 is an enlarged fragmentary view showing a side elevation of one of the rails and end views of a number of the rollers. Fig. 7 is a fragmentary view, partly in section, taken on the line V—V of Fig. 6. Fig. 8 is a longitudinal section through one of the rollers, and Fig. 9 is an end view of one of the rollers.

The fire escape, or device has chute 10 which is tubular in form, and is preferably substantially square, or rectangular in cross section whereby two side walls 11 and 12, a bottom 13, and a top wall 14 are provided. When the fire escape is applied to a building as 14^a, or other structure of more than one story in height the chute 10 is constructed so as to be stationary therewith and is formed to provide integral sections, as 15, 16, 17, with a continuous passage therethrough, and each section is of a length to conform approximately to the height of each story of the building. As shown in the drawings, the sections 15, 16, 17 are disposed upon inclines in opposite directions relatively to each other to prevent too precipitous a descent for persons to slide down the chute when the device is used in conjunction with a high structure. By providing the chute of the shape mentioned it may readily be constructed entirely of cement, or other material which is non-inflammable and a non-conductor of heat, or may be constructed partly of metal and coated with cement, or the like so as to be strictly fire-proof as well as tending to deflect the heat from a burning structure, instead of conducting the heat as is characteristic of fire escapes made of metal.

Interiorly of each of the sections of the chute 10 and adjacent to the bottom thereof is a freely movable floor which serves as a slideway 18 composed of a number of rotatable members, or rollers 18^a which are arranged adjacent to each other and disposed

transversely of the sections of the chute. The rollers 18^a may be of any suitable material, but each is preferably made of a round bar of metal which is covered with cement, as 19, in a manner so that each end of the bar is free of coating to serve as short shafts 20 and 20^a. The shafts 20 and 20^a of each of the rollers are rotatably disposed in spaced bearings provided in rails 21 and 22 one of which is arranged at each side of the bottom 13 of each of the sections of the chute. The sections of the chute 10 are made of dimensions whereby the person sliding therethrough should be in a sitting posture, and the rotation of the rollers will then serve to carry the person in a downward direction as well as tending to prevent the person from stopping his descent by pressing the hands, for instance, against 10 the side walls of the chute. When the chute is constructed of a number of sections, and to check the rapidity of the descent of a person passing therethrough, I may dispense with the use of the rollers 18^a at bends 15 of the chute which form the junctures of the sections, and instead flooring of cement, or 20 the like may be used.

The chute 10 has an entrance 23 at its upper end, and an exit 24 at the lower end 30 thereof. Where the chute has a plurality of sections each one is of a length to extend from one story to the other of the building, and at each story may be constructed in conjunction with the chute a platform, as 25, 26, 27, 27^a. Leading into the sections 16 and 17 from the platforms 26 and 27 are entrances 28 and 29, respectively, to permit persons to depart from various floors of a burning building, and conveniently enter 35 the chute. In order that the persons entering the sections of the chute at its various entrances will be compelled to pass therethrough in the same direction, I provide in the chute at the entrance of each of the sections except the top section a branch slideway, as 30 and 31, each of which is arranged 40 to converge with the main slideway of the chute, and the floor of each of said branch slideways may be free of rollers, or composed of rollers similar to the rollers 18^a. Upon each section of the chute may be provided a stairway, as 32, if desired, which 45 may also be used as a means of escape from a building, and which is adapted to be constructed of cement, or other like material.

In the foregoing description, I have embodied the preferred form of my invention, but I do not wish to be understood as limiting myself thereto, as I am aware that 50 modifications may be made therein without departing from the principle, or sacrificing any of the advantages of this invention, therefore I reserve to myself the right to make such changes as fairly fall within the 55 scope of the appended claims.

Having thus described my invention, I claim as new and desire to secure by Letters Patent:—

1. A device of the character described comprising a fire escape for a building having a plurality of stories, said fire escape including in combination a platform for each story of said building, a rigid integral covered chute including straight portions intermediate each platform, said portions being oppositely inclined one to another, an entrance chute comprising a slide leading from each platform into said integral chute, turns in said integral chute being formed adjacent to said entrance chutes, said entrance chutes being inclined at a greater inclination than the inclination of said turns, the mouth of said entrance chutes and said turns being substantially side by side. 75

2. A fire escape for a building having a plurality of stories including a platform for each story of said building, a rigid integral covered chute provided with an open stairway on the upper side thereof, said integral chute including oppositely inclined portions 90 and an entrance chute for each platform leading into said integral chute beneath the respective platform from which said entrance chute leads, substantially as described. 95

3. A fire escape for a building having a plurality of stories including a platform for each story of said building, a rigid integral covered chute substantially rectangular in cross section, the upper portion of said chute comprising a stairway terminating in the planes of its respective platforms, and the lower inclosed portion of the chute comprising a slide, the bottom of which at each platform is below the platform a distance substantially equivalent to the depth of the chute. 100

4. A fire escape for a building having a plurality of stories including a platform for each story of said building, a rigid integral covered chute substantially rectangular in cross section, the upper portion of said chute comprising a stairway terminating in the planes of its respective platforms, the lower inclosed portion of the chute comprising a slide, the bottom of which at each platform is below the platform a distance substantially equivalent to the depth of the chute, and entrance chutes leading from each platform downwardly into said covered chute. 110

5. A fire escape for a building having a plurality of stories including a platform for each story of said building, a rigid integral covered chute comprising oppositely inclined sections, turns connecting said sections, the inclination at said turns being materially lessened, and entrance chutes on each of said platforms, said entrance chutes having an inclination equal to that of the main chute sections. 125

6. A fire escape for a building having a plurality of stories including a platform for each story of said building, a rigid integral covered chute comprising oppositely inclined sections, turns below the level of the platforms connecting said sections, the inclination at said turns being materially lessened, and entrance chutes for each of said platforms having an inclination equal to that of the main chute section, said entrance

chutes being substantially concentric with the turns throughout the greater portion of their length and leading into said chutes at points below said platforms.

This specification signed and witnessed 15 this twentieth day of December A. D. 1912.

MAX ROSNER.
